UNITED STATES PATENT OFFICE.

M. H. MERRIAM AND E. L. NORTON, OF CHARLESTOWN, MASSACHUSETTS.

IMPROVED APPARATUS FOR DRYING HIDES.

Specification forming part of Letters Patent No. 55,333, dated June 5, 1866.

To all whom it may concern:

Be it known that we, M. H. MERRIAM and E. L. NORTON, both of Charlestown, in the county of Middlesex and State of Massachusetts, have invented an Improved Apparatus for Drying Skins; and we do hereby declare that the following, taken in connection with the drawings which accompany and form part of this specification, is a description of our invention sufficient to enable those skilled in the art to practice it.

The invention relates to the construction of an apparatus for drying skins by exposure to heat and currents of air within a drying-case; and the invention consists of a series of sliding panels for holding the skins supported in guide-rails, and capable of such movement with respect to a door or opening in the drying-case in which they are contained that each panel may be entered and withdrawn at such opening for the purpose of attachment and removal of the skins; also, in the combination, with such drying-case, movable rails, and sliding panels, of a stationary frame or rail placed outside of the case and in such position with respect to the door in the case that each panel may in turn be slid out into such frame and back into the drying-case, for the more convenient attachment and removal of the skins; also, in the arrangement of the system or series of panels radially around an axis in the center of the drying-chamber; also, the combination, with the stationary drying case or chamber and the movable series of rails and panels, of heating-pipes or their equivalents.

An apparatus embodying the invention is represented in the drawings, Figure 1 showing a side elevation, Fig. 2 a horizontal section, and Fig. 3 a central vertical and transverse section, the same.

a denotes the casing, suitably erected on a bed or platform, *b*, and having inlet-passages *c*, for the free ingress of air into the chamber formed by the casing, and provision at top for the escape of such air, so as to maintain a circulation through the chamber.

d denotes a coil of pipe communicating with a suitable steam or heat generator, and extending around within the drying-chamber for the purpose of heating the same.

e are panels, the opposite ends of each of which run in grooves or guide-rails *f*. The

rails extend radially from a shaft, *g*, to a ring, *h*, the two sets of rails at the opposite ends of the case forming heads for the support of the panels in radial position, as seen in Fig. 2.

The shaft *g* is journaled in the bed or platform *b* and in the top of the casing *a*, so that by rotation of the shaft the series of panels are rotated, as will be readily understood. On one side of the casing is a door or opening, *i*, and the platform *b* is extended out at such side to support a stationary frame, at the opposite ends of which are two guide-groove or ways, *l*, extending to the door *i*. When the door is open the rotation of the shaft *g* brings each movable rail or set of rails into line with the stationary rails, and so that each panel may in turn be run out from the casing upon the ways *l* for removal of the dried skins from the opposite surfaces of the panel and the attachment of fresh skins thereto, the panel being slid back into the case after the skins have been fastened theronpon, so that the shaft *g* may be turned to bring the next panel into position to be slid out.

It will be obvious that a series of movable panels and guide grooves or rails may be arranged parallel to each other in a rectangular box, in combination with one or more openings or one or more stationary frames; but though our invention embraces such arrangement, we consider the radial series of panels preferable, both on account of the greater compactness of the parts and the greater ease with which the panels may be handled.

In charging the apparatus the wet skins are nailed or fastened to each panel in turn, and the heat within the casing and the circulation of air through the same are so graduated that during the passage of the panels once around the casing the skins become fit for removal, so that the operation of charging and removal may be continuously carried on.

Generally a free circulation of air is permitted directly through the drying-chamber; but the top of the chamber is to be connected with a main flue or ventilating-tube, by closing or partially closing a damper in which the current of air may be regulated when there may be a tendency in the skins to become too dry in their passage.

We claim—

1. A series of sliding panels arranged within

a drying chamber or case and made movable with respect to an opening or door in such case, so that each panel as it is brought opposite to such opening may be wholly or partially withdrawn from the casing for the attachment and removal of the skins.

2. In combination with the series of panels and the movable rails which support the same, a stationary frame having ways upon which each panel is guided and supported as it is slid from the drying-chamber.

3. The radial arrangement of the movable

series of panels in the drying-chamber, substantially as set forth.

4. The combination, with the stationary case and movable system of sliding panels, of heating-pipes or their equivalents, substantially as set forth.

In witness whereof I have hereunto set my hand this 24th day of November, A. D. 1865.

M. H. MERRIAM.

Witnesses: E. L. NORTON.
